FLATIRON

Joseph W. Myers, Philadelphia, Pa., assignor to
Proctor & Schwartz Electric Co., Philadelphia,
Pa., a corporation of Pennsylvania

Application March 22, 1934, Serial No. 716,874

9 Claims. (Cl. 219—25)

This invention relates to electrically heated flat-irons and, more particularly, to that part of the iron known as the sole plate and the heating means therefor. The principal object of the 5 invention is to provide a novelly constructed sole plate and heating unit, the unit being embedded in refractory cement within a slot or slots in the sole plate.

The embedding of the heating element of a 10 flat-iron in refractory cement is not broadly new but heretofore the heating coil has been disposed in multiple loops lying flat in a plane parallel to the bottom of the iron. This arrangement has the objection that the heat from the coils 15 can only be abstracted from the side of the heating unit that is adjacent the sole plate of the iron. Then too, there is the further objection that a relatively large area of the refractory cement is exposed to the moisture in the air 20 which lowers the resistance of the unit to ground. If it is attempted to exclude the moisture by the use of a cover, considerable difficulty is involved.

In accordance with the present invention, the 25 sole plate is formed so as to provide a channel therein which is as narrow as possible considering the diameter of the resistance coil to be embedded. I am aware that narrow milled slots have been used heretofore in flat-irons and like devices, but such slots have contained a sinuous 30 conductor or large flattened helix usually insulated with mica. As far as I know, I am the first one to embed under pressure the heating unit in a refractory cement within such a slot.

A preferred feature of the invention resides 35 in the use of a channel or slot which is deep enough to permit of using two superposed coils arranged as hereinafter described and having the advantages hereinafter set forth.

A further feature of the invention resides in 40 the use of a novelly constructed and arranged cover for the slot which has definite advantages as hereinafter described.

Other objects and improved features of the 45 invention will be apparent hereinafter from the following detailed description of the preferred structure illustrated in the drawing, in which:

Fig. 1 is a side elevational view of the complete iron;

Fig. 2 is a perspective view of the sole plate and its associated heating unit;

Fig. 3 is a sectional view along line 3—3 of Fig. 2;

Fig. 4 is a sectional view along line 4—4 of 55 Fig. 2;

Fig. 5 is a perspective view of the slot cover; and

Fig. 6 is a diagrammatic perspective view illustrating the arrangement of the heating coils.

Referring now to the drawing, the iron comprises the usual sole plate 1, cover 2 and handle structure 3. Referring particularly to Figs. 2, 3 and 4, the sole plate is formed so as to provide a channel-like slot 4 extending along the sides and back, and defining a central area 5 which is preferably recessed and adapted to seat a thermostatic switch unit 6 which forms the subject matter of my copending application, Serial No. 716,873, filed March 22, 1934. It will be seen that slot 4 comprises side slots running lengthwise of the iron and connected at the rear by a transverse slot.

As shown more clearly in Fig. 4, the slot is 20 preferably formed so that it is deeper than it is wide and it is thus adapted to receive the superposed portions of a unitary heating unit 7. The slot may, of course, take shapes other than that shown and it may have any desired dimensions. The heating unit is embedded in a refractory insulating material 8 which may take the form of 25 any suitable refractory body which is commonly used in flat-irons or like devices. The insulating material substantially fills the slot and is highly compressed therein so as to support the heating unit in desired relation with respect to the sole 30 plate.

By having the slot deep enough to use superposed sections of the heating unit, it is possible to use a relatively heavy conductor instead of a single loop of a fine conductor. In other words, 35 the desired resistance is had by the use of a larger conductor of relatively longer length. The heating unit terminals are shown at 9 and it will be seen that the unit enters the slot at the rear central portion thereof and passes successively in 40 loops through the side portions of the slot, returning to the point where it enters (see Fig. 6). Thus, there is provided in each of the side slots two superposed conductors forming a loop. By 45 this arrangement, the heating element gives off more heat to the side walls of the slot than to the top or bottom thereof.

A metal cover 16, which is preferably formed of sheet steel, holds the refractory material and the 50 embedded heating unit securely in place. This cover may be formed in two sections, as clearly illustrated in Fig. 5. The rear ends of the cover sections may be bridged by mica sheets through which the heating unit terminals may extend, as 55 shown in Figs. 2 and 3. Preferably, the cover

has its edges bent downward and engaging the sides of the slot as at 11. The cover forms a tight seal with the walls of the slots so as to exclude atmospheric moisture from the refractory insulation in which the heating element is embedded. The arrangement of the cover with the walls of the slot wedges the cover securely in place and resists any expansion of the refractory material resulting from the release of the very high pressure with which the cover is pressed into position directly on top of the insulating material and also from the thermal expansion of the refractory material when it is heated by the embedded unit. Any expansion of the refractory material tends to force the depending sides of the cover outward into greater frictional engagement with the walls of the slot, thus tending to more securely lock the cover in place.

A further advantage of the cover is that it transmits the heat which it receives from the top of the refractory insulation to the side walls of the slot. This heat conductivity of the cover to the side walls is particularly pronounced owing to the fact that it is quite narrow. As a result of this and the fact that the heating unit is surrounded on three sides by the sole plate, substantially the same thermal efficiency is obtained from the unit as though it were entirely cast into the sole plate, without the disadvantages incident to casting the unit into the sole plate, such as expensive manufacture, foundry losses, etc. This structure is economical in manufacture, highly resistant to moisture, and obtains maximum possible thermal efficiency.

It is further contemplated by the invention to provide a tilting support 12 in the form of a metallic rod bent as illustrated clearly in Fig. 2 and having its ends embedded in the sole plate as at 13. This affords a simple and inexpensive way of rigidly and firmly securing the rod in desired position so that it extends from the back of the iron, as clearly illustrated. The function of this member is, of course, to enable tilting of the iron on its end during periods of non use, particularly when the iron is hot.

It will be seen that the structure of the iron as a whole is compact and simple. The heating unit structure enables the mounting of the thermostatic switch unit in a central recess and in intimate contact with the hottest part of the sole plate. This arrangement greatly enhances the efficiency of the iron.

Although the invention has been illustrated and described with reference to a preferred form, it will be understood that various modifications are possible without departing from the spirit and scope of the invention. In its broad aspect, the invention contemplates the provision of a narrow slot in the sole plate and the embedding of a conductor in refractory cement within the slot.

I claim:

1. In a flat-iron, a metallic plate or block to be heated having formed therein a slot of considerably greater depth than width, an electrical heating element comprising at least two superposed conductors disposed within said slot, and compressed refractory insulating material surrounding said element and supporting the same in said slot in proper relation to said plate.

2. In a flat-iron, a metallic plate or block to be heated having formed therein a slot of considerably greater depth than width having a portion running lengthwise of the iron, an electrical heating element disposed within said slot,

said element having a portion running from back to front in said slot portion and returning in said slot portions with the forwardly and rearwardly running portions of the element in superposed relation in said slot portion, and compressed refractory insulating material surrounding said element and supporting the same in said slot in proper relation to said plate.

3. In a flat-iron, a sole plate having formed therein a slot of considerably greater depth than width running around the top of the plate, an electrical heating element having its terminal ends at the rear of the iron and comprising superposed sections running forward and backward in a single portion of said slot, and compressed refractory insulating material surrounding said element and supporting the same in said slot in proper relation to said plate.

4. In a flat-iron, a sole plate having formed therein a plurality of slots of considerably greater depth than width running lengthwise of the iron, an electrical heating element having its terminal ends at the rear of the iron and comprising successive loops disposed respectively in said slots with the sides of each loop in superposed relation, and compressed refractory insulating material surrounding each loop and supporting the same in its slot in proper relation to said plate.

5. In a flat-iron, a sole plate having formed therein a slot of considerably greater depth than width running around the top of the plate, an electrical heating element having its terminal ends at the rear of the iron and comprising successive loops disposed respectively in portions of said slot with the sides of each loop in superposed relation, and compressed refractory insulating material surrounding said element and supporting the same in said slot in proper relation to said plate.

6. In a flat-iron, a metallic plate or block to be heated having a slot formed therein, an electrical heating element disposed within said slot, compressed refractory insulating material surrounding said element and supporting the same in said slot in proper relation to said plate, and an inverted channel-shaped sheet metal cover disposed in said slot with said material between the depending flanges of said cover, whereby expansion of said material forces the cover more securely in place and displacement of the cover due to such expansion is effectively prevented.

7. In a flat-iron, a metallic plate or block to be heated having a slot formed therein, an electrical heating element disposed within said slot, compressed refractory insulating material surrounding said element and supporting the same in said slot in proper relation to said plate, and a sheet metal cover closing the slot and having its edges bent downward into binding contact with the slot walls with said material between the cover edges, whereby expansion of said material forces the cover more securely in place and displacement of the cover due to such expansion is effectively prevented.

8. In a flat-iron, a metallic plate or block to be heated having a slot formed therein, an electrical heating element disposed within said slot, compressed refractory insulating material surrounding said element and supporting the same in said slot in proper relation to said plate, and a sheet metal cover closing the slot and having a flange extending between the refractory material and wall of the slot and in intimate contact with the wall whereby expansion of said material forces the flange more securely against

the wall of the slot and in intimate contact with a side of the slot which permits of ready transfer of heat from the cover to the slot wall.

9. In a flat-iron, a metallic plate or block to be heated having a slot of greater depth than width formed therein, an electrical heating element comprising superposed conductors disposed within said slot, compressed refractory insulating material surrounding said element and support-

ing the same in said slot in proper relation to said plate, and a sheet metal cover closing the slot and having its edges bent downward into wedging relation with the slot walls with said material between the cover edges, whereby expansion of said material wedges the cover more securely in place and displacement of the cover due to such expansion is effectively prevented.

JOSEPH W. MYERS.
